UNITED STATES PATENT OFFICE

AUGUST KAZENMAIER, OF STUTTGART, GERMANY, ASSIGNOR TO ROBERT BOSCH
AKTIENGESELLSCHAFT, OF STUTTGART, GERMANY

CARBURETOR

Application filed August 11, 1930, Serial No. 474,477, and in Germany September 11, 1929.

The present invention relates to self-feeding carburetors having air throttle and float chamber regulation in which the air space of the float chamber is connected to one choke tube whilst the fuel space of the float chamber is connected to another choke tube in which the vacuum is higher than in the first choke tube. In order to prevent an excessively high vacuum arising in the mixing chamber when the air throttle is closed, the mixing chamber of this carburetor can be closed from the engine by a throttle to such an extent that the vacuum arising in the mixing chamber only reaches that degree which is necessary for maintaining the fuel level at the required height in the float chamber that is to say to be able to supply the fuel from a low lying supply tank to the float chamber. As the two throttles are moved together and therefore opened and closed together vacuum is increased in the mixing chamber when the throttles are opened because the high vacuum behind the suction throttle can suddenly act much more strongly on the mixing chamber, and it is not possible for sufficient fresh air to flow through the opening to the choke tube.

In order to avoid this undesirable increase of the vacuum in the mixing chamber the two throttles are so connected together according to the present invention that the air throttle at least at the beginning opens correspondingly more quickly than the suction throttle behind the choke tubes. Fuel is saved in this way and in addition the suction noise is reduced.

One form of construction according to the invention is shown by way of example in the accompanying drawing.

The mixing tube *a* has a main choke tube *b* in which is disposed an auxiliary choke tube *c*. The throat of the nozzle *b* is connected to the air space of a float chamber *e* by a passage *d*. A pipe *f* leads from the fuel space of the float chamber to the throat of the nozzle *c*. A constriction *a* is provided in the pipe *f* for governing the passage of fuel. The air throttle *h* has a lever *i* which is connected through a rod *k* to a lever *m* of the throttle valve *n*. Behind the choke tubes *b*, *c*, is a calibrated opening *o* in the mixing tube *a*

for regulating the vacuum when the throttle *n* is closed.

The levers *i* and *m* are secured to their axles in such a way that the rod *k* makes an acute angle α with the lever *i* and an obtuse angle β with the lever *m* when both throttle valves are closed. When the throttle valve *h* is opened for an angle γ the throttle valve *n* opens for only the substantially smaller angle δ . The levers *i* and *m* and the throttle valves *h* and *n* are preferably so disposed from each other that the two throttle valves simultaneously move into their end position to be opened completely. (See the dotted lines in the figure.)

I claim:

1. A self feeding carburetor comprising a mixing tube, at least two choke tubes adapted to produce different degrees of vacuum for any given engine suction, a float chamber the air space of which is connected to the choke tube of lower vacuum and the fuel space to the choke tube of higher vacuum, an air throttle in advance of said choke tubes, a second throttle in rear of said choke tubes and means for operating said second throttle in dependence on said air throttle such that the rate of increase of effective cross sectional area past the air throttle is greater on commencement of opening of the same than that past the second throttle.

2. A self feeding carburetor comprising a mixing tube, at least two choke tubes adapted to produce different degrees of vacuum for any given engine suction, a float chamber the air space of which is connected to the choke tube of lower vacuum and the fuel space to the choke tube of higher vacuum, an air throttle in advance of said choke tubes, a second throttle in rear of said choke tubes, operating levers on said air and second throttles and a connecting link between said levers, the disposition of said levers and connecting link being such that when the throttles are closed the lever of the air throttle forms a smaller angle with said link than the lever of the second throttle.

3. A self feeding carburetor comprising a mixing tube, at least two choke tubes adapted to produce different degrees of vacuum for

any given engine suction, a float chamber the air space of which is connected to the choke tube of lower vacuum and the fuel space to the choke tube of higher vacuum, an air throttle in advance of said choke tubes, a second throttle in rear of said choke tubes, operating levers on said air and second throttles and a connecting link between said levers, the disposition of said levers and connecting link being such that when said throttles are closed the effective length of the lever of the air throttle is less than the effective length of the lever of the second throttle so that the rate of increase of effective cross sectional area past the air throttle is greater on commencement of opening of the same than that past the second throttle.

4. A self feeding carburetor comprising a mixing tube, at least two choke tubes adapted to produce different degrees of vacuum for any given engine suction, a float chamber the air space of which is connected to the choke tube of lower vacuum and the fuel space to the choke tube of higher vacuum, an air throttle in advance of said choke tubes, a second throttle in rear of said choke tubes and common operating means for opening and closing said throttles simultaneously, said means operating on commencement of opening movement to rotate the air throttle faster than the second throttle.

5. A self feeding carburetor comprising a mixing tube, at least two choke tubes adapted to produce different degrees of vacuum for any given engine suction, a float chamber the air space of which is connected to the choke tube of lower vacuum and the fuel space of which is connected to the choke tube of higher vacuum, an air throttle in advance of said choke tubes, a second throttle on rear of said choke tubes, means for operating said second throttle in dependence on said air throttle such that the rate of increase of effective cross sectional area past the air throttle is greater on commencement of opening of the same than that past the second throttle, said operating means being further adapted to cause the throttles to reach their fully open or fully closed positions simultaneously.

50 In testimony whereof I have hereunto affixed my signature.

AUGUST KAZENMAIER.
